BARRIER WICKET

Joel Soderholm, Minneapolis, Minn.

Application February 8, 1937, Serial No. 124,705

8 Claims. (Cl. 20—1.01)

My invention relates to improvements in barrier wickets, particularly though not exclusively, for the protection of bank cashiers.

An object of the invention is to provide an improved wicket of the present character through which objects may be readily passed from the patron's station at one side thereof to the attendant's station at the opposite side, and vice versa, in full view of both attendant and patron, such structure constituting an effective barrier that is bullet resistant and which serves to isolate the attendant's station from the station for patrons whom he serves.

More specifically, it is an object of my invention to provide a structure of the instant nature including a counter and a transparent, non-shatterable barrier pane between an attendant's station at one side of the counter and a patron's station at the opposite side thereof, such structure having a counter or deal tray beneath said pane through which papers, currency and the like may be passed from either of said stations to the other, the tray being supplied with simultaneously movable closure panels or transparent non-shatterable glass, one at either side of the barrier pane, each panel being movable into a position covering its respective portion of said tray at its respective side of said barrier pane, such positioning of one closure panel being attended with movement of the other into a position uncovering its respective portion of the deal tray at its respective side of the barrier pane.

Other objects of the invention reside in the novel combination and arrangement of parts and in the details of construction hereinafter illustrated and/or described.

In the drawings, Fig. 1 is a fragmentary perspective view illustrating a barrier wicket embodying my invention; Fig. 2 is a plan view of the structure shown in Fig. 1; Fig. 3 is a sectional view taken as on the line 3—3 of Fig. 2; Fig. 4 is a detail sectional view taken as on the line 4—4 of Fig. 3; Fig. 5 is a fragmentary perspective view of the deal tray proper, and Fig. 6 is a fragmentary perspective view illustrating one of the two closure panels for the tray and the corresponding portion of the panel carrying carriage.

Reference being had to the drawings, it will be seen that the illustrated structure comprises a barrier including a counter 10, window panes 11, 12 and mullions 13 for said panes rising from the counter in a plane paralleling said counter approximately midwidth thereof. Said barrier also includes a drop panel 14 beneath the counter 10.

The barrier pane 12 stands between an at-

tendant's station, 15 at one side of the counter 10, and a patron's station 16 at the other side of said counter. The pane 12, like its companion panes 11, are of bullet resistant material, said pane 12 being transparent and, preferably, of 5 shatter-proof glass.

Set into the counter 10, beneath the pane 12, is a deal tray 17 through which objects, such as bank-books, papers, currency and the like may be passed under the pane 12 from the one station 10 at one side of said pane to the other station at the opposite side thereof.

The body of the tray 17 is trough-shaped, the same being formed of metal and having a substantially flat bottom 18 and upturned sides 19. 15 Said tray is supported at its ends by means of rails 20 formed with depending plates 21 providing hangers for the body of the tray and also forming the ends thereof. Attaching flanges 22 turned outwardly from the body of the tray 17, 20 at the extremities thereof, are secured by screws 23 to the hanger plates 21 on the rails 20. The rails 20 are Z-shaped in cross-section, each thereof having a web 24, an inwardly turned track flange 25 at its lower edge and an outwardly 25 turned attaching flange 26 at its upper edge. The attaching flanges 26 of said rails 20 are riveted or otherwise secured to the lower face of a mounting plate 27 which is cut away centrally thereof to provide an opening 28 therein above the tray 30 17. An opening 29 is cut in the counter 10 to accommodate the rails 20 and the tray 17, said counter being recessed for the reception of the mounting plate 27 to bring the upper face thereof into the plane of the face of the counter. The 35 drop panel 14, beneath the counter 10 is also cut away as at 30, to accommodate the rails 20 and tray 17. Said rails 20 extend transversely of the counter 10, while the body of the tray 17 extends longitudinally thereof, one side portion of the 40 tray being open at one side of the barrier pane 12 and the other side portion of said tray being open at the opposite of said pane.

Mounted for to and fro movement on the track flanges 25 of the rails 20 is a carriage 31 having a 45 rectangular frame consisting of side members 32 and end members 33. At each corner of the carriage frame is a wheel 34, which is journaled on a lug 35 issuing from an end member 33 of the frame. The wheels 34 at each side of the 50 carriage frame are positioned in the plane of the corresponding side frame member 32 and ride the track flange 25 of the corresponding rail 20. The opposite inner marginal portions of the mounting plate 27, paralleling the counter 10, over- 55

reach the end frame members 33 of the carriage 31 in all positions of the carriage and the inner marginal portions of said plate, transversely of the counter, overreach the side members 32 of said frame.

Carried by the carriage 31, in relatively spaced relationship, are a pair of closure panels 36 for the tray 17, one panel for the portion of the tray at one side of the barrier pane 12 and the other panel for the portion of said tray at the opposite side of said pane. These closure panels 36 are of transparent, non-shatterable material, preferably of bullet resistant glass. Said panels 36 extend from one side frame member 32 of the carriage 31 to the other and each panel has a support, at its respective end of said carriage, which consists of an inside flange 37 formed on the frame member 33 at such end of said carriage. Further supporting the spaced closure panels 36 are channeled nose-strips 38, each sheathing the edge of its respective panel 36 and secured at its ends to the side frame members 32 of the carriage 31 by means of screws 39. The lugs 35 at the ends of the carriage 31 extend beyond the wheels 34 journaled thereon and serve to strike the counter 10 at their respective edges of the opening 29 therein and thereby limit the to and fro movement of the carriage. Thus, in either of the extreme positions of the carriage 31, one of the closure panels 36, carried thereby, is projected from beneath its corresponding portion of the mounting plate 27 and positioned to cover its respective portion of the tray 17 at the one side of the barrier pane 12, while the companion closure panel 36 is retracted beneath its corresponding portion of said mounting plate 27 and thereby located in a position uncovering its respective portion of the tray 17 at the other side of said pane 12.

The edges of the upper flanges 40 of the channeled nose-strips 38 are beveled, as at 41, and the facing edges of the mounting plate 27 are similarly beveled, as at 42, to prevent the catching of objects between said strips and plate.

Dual means are provided to prevent the pinching of papers between the edges of the lower flanges 43 of the nose-strips 38 and the lip of the tray 17, the same comprising a pair of guard-strips 44 extending from one rail 20 to the other and slidably supported at their ends on the track flanges 25 of said rails. One guard-strip 44 is located beneath one closure panel 36 coplanar with the flange 43 on its nose-strip 38 and its panel supporting flange 37. The other guard-strip 44 is similarly located with respect to the other closure panel 36. Said guard-strips 44 are similarly shifted into and out of their operative positions, wherein they overhang their respective portions of the lip of tray 17. Each guard-strip 44 in operative position, forms a stop to catch the leading edges of papers, inserted into the tray from the opposite side, and prevents them from entering the path of the flange 43 on the nose-strip 38, where they might be caught between such flange and the tray lip and thereby mutilated as a consequence thereof. Each guide-strip 44 is pushed into its projected or operative position by the carriage frame flange 37 supporting its respective closure panel 36 and is pushed into its retracted or inoperative position by the flange 43 on the nose-strip 38 of its respective closure panel 36. The guard-strip 44 at the left hand side of Fig. 3 is shown in its operative position and the guide-strip 44 at the right hand side of said Fig. 3 is shown in its inoperative position.

The barrier pane 12 projects through the opening 28 in the mounting plate 27, the lower marginal portion of said pane being positioned between the side frame members 32 of the carriage 31, so that the nose-strips 38 on the closure 5 panels 36 will assume positions substantially abutting said portion of said pane.

Having reference to Fig. 3 of the drawings, the manner in which objects may be passed through the barrier structure will be readily understood. 10 Assume that a patron at the patron's station 15 wishes to pass a check through the barrier wicket to the attendant at the attendant's station 16. Such check would be slipped into the tray 17 through the space between the retracted 15 closure panel 36 and the barrier pane 12. Thereafter, the patron or attendant, each having access to the nose-strip 38 of his respective closure panel 36, would push or pull upon such strip, as the case may be, to shift the carriage 31 and 20 reverse the relation between closure plates 36 and barrier pane 12. This accomplished, the check in tray 17 would be accessible to the attendant through the opening between the closure panel 36 and the barrier pane 12 at his station 25 16. Should the transaction call for the exchange of currency for the check, the attendant would slip the currency into the tray 17 through said opening between said panel 36 and pane 12 and, thereupon, slide the carriage 21 to reposition the 30 same in its relation with respect to the barrier pane 12 as shown in Fig. 3. The currency in the tray 17, in such position of the carriage, would then be accessible to the patron through the opening between the barrier pane 12 and closure 35 panel 36 at his station 15. The pane 12 and closure panels 36 being transparent, it is possible at all times for both patron and attendant to view objects within the tray 17 and each party is able to see the objects as they are placed in 40 and taken from the tray by the other party.

All of the parts of the barrier structure, including the pane 12 and closure panels 36, being of bullet resistant material, it is impossible, from the patron's station 15, to inflict injury upon the 45 attendant at his station 16, since no bullet or other weapon could reach the attendant through the tray 17 or other portion of the barrier. With the portion of the tray 17 at the attendant's side of the pane 12 covered by the corresponding 50 closure panel 36, it is obvious that no bullet could pass said panel, and even with said portion of the tray entirely uncovered, it will be seen that a bullet directed into the tray 17 from the patron's station 15 would be intercepted and 55 stopped by the closure panel 36 at the attendant's side of the barrier pane 12. And, too, it will be seen that a bullet directed into an opening of any size between the barrier pane 12 and closure panel 36 at the patron's side of said pane, would 60 be deflected by the bottom 18 of the tray 17 in such manner as to be intercepted and stopped by the then only partially retracted closure panel 36, at the attendant's side of the pane 12.

My invention is particularly advantageous in 65 that it can be readily embodied in a structure which, though relatively simple and inexpensive, is highly effective for the purpose intended, and convenient in use and slighty in appearance.

Changes in the specific form of my invention, as herein disclosed, may be made within the scope of what is claimed without departing from the spirit of my invention.

Having described my invention, what I claim 75

as new and desire to protect by Letters Patent
is:

1. A barrier structure including an upright barrier pane, a deal tray therebeneath, said tray extending beyond the pane at either side thereof and providing a passageway through which objects may be passed from one side of said pane to the other, a carriage interposed between said pane and tray, rails supporting said carriage for to and fro movement, companion closure panels for said tray, said panels being mounted on the carriage in coplanar and relatively spaced relationship, one at one side of said pane and the companion panel at the other side thereof, the plane of the lower edge of said pane being beneath the plane of the upper surfaces of said panels, the movement of said carriage in one direction serving to shift the panels causing one thereof to cover its respective portion of the tray and causing the other to uncover its respective portion of said tray, the reverse movement of said carriage reversing such relationship between panels and tray, nose-strips framing the facing edges of said panels, each strip having a flange underlying its respective panel, a pair of guard-strips, one for each panel, each of said guard-strips being located beneath its respective panel and slidably supported at its ends on said rails for movement into and out of operative position, overhanging its respective lip portion of said tray, wherein it serves as a stop for the leading edges of papers inserted into the tray from the opposite side thereof, means on the carriage for engaging said guard strips and moving the same into their said operative positions, the flanges on said nose-strips being in a plane common to that of said guard-strips, and providing means for engaging said guard-strips and retracting them from their said operative positions.
2. A barrier structure including an upright pane of transparent material, a deal tray therebeneath, said tray extending beyond the pane at either side thereof and providing a passageway through which objects may be passed from one side of said pane to the other, a carriage interposed between said pane and tray and supported for to and fro movement, companion closure panels for said tray, said panels being of transparent material and mounted on the carriage in relatively spaced relation, one at one side of said pane and the companion panel at the other side thereof, said panels being in a common plane occupied by the lower marginal portion of said pane, the movement of said carriage in one direction serving to shift the panels causing one thereof to cover its respective portion of the tray and causing the other to uncover its respective portion of said tray, the reverse movement of said carriage reversing such relationship between panels and tray, and stop means to limit the extent of the to and fro movements of said carriage and thereby keep said panels from striking said lower marginal portion of the barrier pane.
3. A barrier structure including an upright pane, a deal tray therebeneath, said tray extending beyond the pane at either side thereof and providing a passageway through which objects may be passed from one side of said pane to the other, a carriage interposed between said pane and tray and supported for to and fro movement, companion closure panels for said tray, said panels being mounted on the carriage in spaced relationship, one at one side of said pane and the companion panel at the other side thereof, and both of said panels above the plane of the lower
- edge of said pane, the movement of said carriage in one direction serving to shift the panels causing one thereof to cover its respective portion of the tray and causing the other to uncover its respective portion of said tray, the reverse movement of said carriage reversing such relationship between panels and tray, abutment means on the barrier structure, and means on the carriage for engagement with said abutment means to limit the to and fro movements of said carriage.
4. In a structure of the present character, a barrier including an upright pane, a deal tray therebeneath, said tray extending beyond the pane at either side thereof and providing a passageway through which objects may be passed from one side of said pane to the other, a carriage interposed between said pane and tray and supported for to and fro movement, companion closure panels for said tray, said panels being mounted on the carriage in coplanar and relatively spaced relationship, one at one side of said pane and the companion panel at the other side thereof, and both of said panels above the plane of the lower edge of said pane; the movement of said carriage in one direction serving to shift the panels causing one thereof to cover its respective portion of said tray and causing the other to uncover its respective portion of said tray, the reverse movement of said carriage causing the one panel to uncover its respective portion of the tray previously covered thereby and causing the companion panel to be re-positioned and thereby disposed in tray covering relation, guard strips, one for each closure panel, each guard strip being located beneath its respective panel and movable into and out of position over-reaching the lip of its respective side of said tray, and means for shifting said strips to project the one as its respective closure panel takes tray covering position and to retract the other, as its respective panel takes tray uncovering position.
5. In a structure of the present character, a barrier including an upright barrier pane, a deal tray beneath and contiguous to the lower edge of said pane, said tray extending beyond the pane at either side thereof and providing a passageway through which objects may be passed from one side of said pane to the other, companion closure panels, one for that portion of the tray at one side of the barrier pane and one for that portion of said tray at the opposite side of said pane, said closure panels being movably mounted and shiftable to cover and uncover their respective portions of said tray, and means for coordinating the movement of said closure panels, whereby the shifting of one into position covering its respective portion of said tray will be attended with the shifting of the other into position uncovering its respective portion of said tray, said barrier pane and closure panels being of transparent bullet resisting material isolating the stations at either side of the pane, one from the other, and affording a clear view of the contents of said tray from both stations.
6. In a structure of the present character, a barrier including an upright pane, a deal tray therebeneath, said tray extending beyond said pane at either side thereof and providing a passageway through which objects may be passed from one side of said pane to the other, a pair of edgewise spaced closure panels for said tray, one panel being located at one side of said pane and the companion panel at the other side thereof, each panel being disposed in a plane occupied by a lower marginal portion of said pane; said panels

- being slidably guided for concurrent to and fro movement, each in its own plane, above said tray, the movement of said panels concurrently in one direction causing one panel to cover its respective portion of said tray and causing the companion panel to uncover its respective portion of the tray, the movement of said panels in the other direction reversing such relationship between panels and tray.
5. In a structure of the present character, a barrier including an upright pane, a deal tray beneath and contiguous to the lower edge of said pane, said tray extending beyond the pane at either side thereof and providing a passageway 10 through which objects may be passed from one side of said pane to the other, companion closure panels, one for that portion of the tray at one side of the barrier pane and one for that portion of said tray at the opposite side of said pane, said 15 closure panels being movably mounted and shift-

able to cover and uncover their respective portions of said tray, and means for coordinating the movement of said closure panels, whereby the shifting of one into position covering its respective portion of said tray is attended with the shifting of the other into position uncovering its respective portion of said tray. 5

8. In a structure of the character described, a barrier including an upright pane, a tray disposed beneath said pane contiguous thereto, a portion of said tray at one side thereof opening at one side of the pane and the opposite portion of said tray opening at the other side of said pane, companion closure panels, one for each of said portions of said tray, said panels being movable 15 into and out of their respective tray closing positions, each panel in its closed position occupying a plane also occupied by a lower marginal portion of said pane.

JOEL SODERHOLM. 20
